DESIGN FOR A WINCH

Ola L. Berby, Duluth, Minn., assignor to Clyde
Iron Works, Inc., Duluth, Minn., a corporation
of Minnesota

Application June 21, 1945, Serial No. 120,233

Term of patent 14 years

(Cl. D41—1)

To all whom it may concern:

Be it known that I, Ola L. Berby, a citizen of the United States, residing at Duluth, county of St. Louis, and State of Minnesota, have invented a new, original, and ornamental Design for a Winch, of which the following is a specification, reference being had to the accompanying drawing, forming part thereof.

Figure 1 is a perspective view of a winch showing my new design;

Figure 2 is a top plan view of the same; and
Figure 3 is an end elevational view of the same.

I claim:

The ornamental design for a winch, as shown.

OLA L. BERBY.
